US00D880298S

(12) **United States Design Patent** (10) Patent No.: **US D880,298 S**
 Spang, Jr. et al. (45) Date of Patent: ** Apr. 7, 2020

(54) **ACTUATOR**(71) Applicant: **S. C. Johnson & Son, Inc.**, Racine, WI (US)(72) Inventors: **Ronald H. Spang, Jr.**, Kenosha, WI (US); **Richard M. Parysek**, Oak Creek, WI (US); **Steven A. Zach**, Waterford, WI (US); **Marilyn M. Johnson**, Wauwatosa, WI (US); **Imtiaz A. Musaliar**, Evanston, IL (US); **Neema Pourian**, Chicago, IL (US); **Jose L. Padilla**, Cicero, IL (US); **Katherine A. Reiser**, Mount Prospect, IL (US)(73) Assignee: **S. C. Johnson & Son, Inc.**, Racine, WI (US)(**) Term: **15 Years**(21) Appl. No.: **29/661,390**(22) Filed: **Aug. 27, 2018**(51) LOC (12) Cl. **09-07**

CLAIM

The ornamental design for an actuator, as shown and described.

DESCRIPTION

FIG. 1 is an isometric view of a top, front, and right side of an actuator;

FIG. 2 is a front elevational view of the actuator of FIG. 1; FIG. 3 is a rear elevational view of the actuator of FIG. 1; FIG. 4 is a right side elevational view of the actuator of FIG. 1;

FIG. 5 is a left side elevational view of the actuator of FIG. 1;

FIG. 6 is a top plan view of the actuator of FIG. 1; and, FIG. 7 is a bottom plan view of the actuator of FIG. 1.

The dash-dash-dash broken lines are included for the purpose of illustrating portions that form no part of the claimed design.

1 Claim, 7 Drawing Sheets
